SHIFTING INK PAD FOR SELF INKING STAMPERS

Paul L. Clausing, 551 Hamilton St., Ottumwa, Iowa

Filed June 3, 1959, Ser. No. 817,784

8 Claims. (Cl. 101—334)

My invention relates to improvements in self-inking, tumbler type stampers for marking flat or approximately flat surfaces. Such stampers ordinarily comprise a plurality of parallel type-bearing strips mounted for individual adjustment about a central carrier. This carrier is frequently called a "tumbler" because it is so mounted as to reverse itself endwise each time the stamp is used in order that on each stroke the type may be first brought into contact with an inking pad at the top of the cage in which the tumbler is mounted, and then be exposed at the bottom of this cage so that it may be pressed against the surface to be marked. The common fault of existing self-inking stampers of this type is that the individual type on each strip always come into contact with exactly the same spot on the inking pad at each stroke. Because the inking pad is made of a spongy or felt like material in order to be ink absorbent, this material rapidly becomes compressed and packed at the particular points at which it is repeatedly struck by the type on each strip. This is known as "pattern packing." Since the type is usually spring pressed against the ink pad when the stamper is not in use, this packing can occur while the stamper is on the dealer's shelves, before the stamper is even used. Once it has been so compressed, the pad will no longer absorb ink at these points and feed it properly to the type. While the greater part of the pad, which does not come into contact with the type, may still be absorbent, the pad is useless, and must be replaced.

While it would be possible to mount the inking pad on a cylinder and gear this cylinder to the tumbler so that the pad would rotate therewith, the gearing would involve considerable additional expense, and the type would then merely pack a plurality of points on the pad, distributed in rings about the cylinder, for once a revolution of the cylinder had been completed each successive type contact would be made at the exact spot at which a type contact had been made on the previous revolution.

I have found, however, that if the ink pad is made in the form of a disc, and loosely mounted in a cage so that it can dance about therein as the stamper is used, it will tend to rotate and slide in such a random manner that virtually its entire surface will be contacted by the type, thus preventing packing at any one point, or even at a plurality of frequently used points. This arrangement is thus not only chaper, but much more effective than a cylindrical mounting for the inking pad.

The object of my invention is therefore to provide a rotatable inking pad for a self-inking tumbler type stamper and means for loosely mounting it in a suitable cage for free random movement therewithin. Advantageously, the pad should also be readily removable for replacement.

One specific embodiment of my invention will now be described in conjunction with the following drawings in which:

Fig. 1 is a side view showing my new stamper;

Fig. 2 is a front view of the stamper;

2

Fig. 3 is a partial vertical section taken along the line III—III of Fig. 2;

Fig. 4 is a horizontal section taken along the line IV—IV of Fig. 1;

Fig. 5 is a perspective view of my stamper;

Fig. 6 is a partially exploded view of my stamper, with the tumbler actuating means broken away, showing how my inking pad is mounted in the stamper.

Like reference characters denote like parts throughout the several views.

Referring now to Figure 5, it will be seen that my stamper comprises a conventional lower frame or cage 10 provided with an opening 11 at its lower end through which the type is projected for stamping, and the customary rubber pads 9 to prevent marring of any object upon which the stamper is placed. A type carrier 12 is pivotally mounted in this cage to turn about the horizontal axis 13. The top of the frame 10 is formed by a cross-piece 14, on which the stem 15 is mounted. A hollow handle or plunger 16 is slidably mounted on the stem 15 and a fork 17 is fixed thereto. The two arms of this fork are adapted to slide on the vertical sides of the frame 10, and are slotted at 18 to receive pin 19, fixed to the type carrier 12, which extends through slots 20 in the vertical sides of the cage 10. These slots have semi-circular portions so that as the plunger 16 is pushed down, the pin 19 travels therein, and turn the type carrier 12 about the axis 13, before pressing the type against the surface to be stamped. A spring 21 (Fig. 3) automatically returns the type carrier to its original position when the plunger is released, and in that position the type contacts and is spring pressed against the inking pad 22 (Figs. 3, 4 and 6). The position of each individual type bearing strip 23 may be adjusted to expose any desired character thereon by turning the particular knurled disc 23a associated therewith.

All of the mechanism thus far described is of a conventional nature, except for the inking pad 22 and its mounting. This pad consists of a disc of absorbent material 22a, such as felt or the like, embedded in a shallow cup 22b of a relatively ink proof and rigid material, such as metal.

The pad is loosely mounted in a cage formed by the crosspiece 14, portions of the vertical sides of the frame 10, and two identical clips 24 (seen best in Fig. 6). These clips each comprise a slightly resilient U-shaped vertical portion, a lower ledge 24a, and an upper ledge 24b. The two arms of the U-shaped portion are provided with outwardly projecting bosses 25 which snap into holes 26 in the vertical sides of the frame 10. These holes are formed by striking the metal of the side frames inwardly, thereby forming below the holes 26 small shelves 27 on which the lower edges of the clips 24 can rest. The upper ledges 24b of the clips fit into notches 28 in the cross-pieces and are supported thereon. The lower ledges 24a support the inking pad 22. The cross-piece 14 is provided with horizontally extending projections 29 which fit into mating slots in the side frames 10. Between these projections 29 a longer tongue 30 is bent down and welded to the side frames 10. The vertical edges of this projection serve as stops for the clips 24 when they are inserted into the frame.

Attention is drawn to the clearances shown between the ink pad 22 and the sides and top of its cage respectively, which are best seen in Figs. 3 and 4. These are critical to the successful operation of the device. The first of these clearances must be sufficient to permit the pad to shift horizontally the width between the type characters, but insufficient to permit the pad to fall off the ledges 24a. The clearance between the pad and the top of its cage, i.e. the cross-piece 14, is even more important.

This space permits the ink pad to drop and bounce when the stamper handle is pushed down to perform a stamping operation. When the stamper is not in use, spring 21 turns the type carrier to its upper ink pad contacting position, and the distance between the bottom of the ink pad cage and the axis of about which the type carrier turns is shorter than that between this axis and the face of the type which contacts the ink pad, so that the ink pad is lifted up within its cage and pressed against cross-piece 14. When the stamper is in this position, there is then a space between the edges of the ink pad and the supporting ledges 24a. As illustrated in Fig. 3, the stamper handle has been pushed down enough to remove the type from the ink pad. When the stamper is operated, the handle is suddenly pushed down, the type strip carrier 12 turned end for end, and the type suddenly taken away from beneath the ink pad. The ink pad loses its support and drops to the ledges 24a. Since the whole stamper is moving downward rapidly, the ink pad is, literally, thrown against these ledges to produce a bouncing, shifting, dancing, revolving effect. Because of this permitted play, the ink pad cannot possibly stop in exactly the same place each time, and since the shifting is not mechanically controlled, but left entirely to chance, there can be no periodic repeating. The ink pad is round, so it can and does revolve, but it does not revolve about any exact center. Consequently, the ink pad, in my invention, will not "spot pack" or "pattern pack." The "packing" is distributed over the entire pad, giving it many times longer life than rigidly held ink pads.

It will be appreciated that my invention is not limited to the specific embodiment hereinbefore described, but may be embodied in tumbler type stampers differing therefrom in structural details without thereby departing from the spirit of my invention as defined by the following claims.

What I claim is:

1. A tumbler type self-inking stamper of the kind comprising a frame, an ink pad supported on said frame, type carrying means pivotally mounted in said frame, and means for pivoting said type carrier from a first position in which the type thereon is in contact with said ink pad to a second position in which said type is projected from said frame to apply an indicia to a suitable surface, said stamper being characterized by the fact that it comprises a cage extending transversely across said frame in which said ink pad is rotatably enclosed, said cage having an opening in its bottom positioned to receive said type but too small to pass said ink pad, the inner dimensions of said cage in directions both transverse to and longitudinally of said frame being substantially greater than external dimensions of said ink pad in said directions, said ink pad being freely and randomly movable in all directions within the periphery of said cage.

2. A stamper as claimed in claim 1 in which said ink pad is circular.

3. A stamper as claimed in claim 1 in which the difference between the external dimensions of said ink pad and the internal dimensions of said cage in a direction transverse to said frame is at least as great as the transverse distance between the type on said carrier.

4. In combination an ink pad for a stamper and a cage in which said pad is rotatably enclosed, said cage having an opening in its bottom dimensioned to admit type but too small to pass said pad, the inner dimensions of said cage being substantially greater than the corresponding outer dimensions of said ink pad, and said ink pad being freely and randomly movable therein.

5. A stamper as claimed in claim 1 in which said frame comprises two vertical side members and said cage comprises a transverse member fixed therebetween to constitute the top of said cage, together with two opposed clip members provided with U-shaped portions dimensioned to fit between said side members and constitute the sides of said cage, said clips carrying upper ledges positioned and dimensioned to rest on said transverse member, and lower ledges adapted to support the edges of said ink pad and constitute two sides of said opening.

6. A stamper as claimed in claim 5 in which said clips are resilient and the arms of said U-shaped portions carry catch means adapted to snap into engagement with mating means on said side members.

7. A hand-operated tumbler type self-inking stamper of the kind comprising a frame, an ink pad supported in said frame, type-carrying means pivotally mounted in said frame, and means for pivoting said carrier from a position in which the type thereon is in contact with said ink pad to a position in which said type is projected from said frame to apply an indicia, said stamper being characterized by the fact that said ink pad is rotatably enclosed within a cage having an opening in its bottom positioned and dimensioned to admit said type but too small to pass said ink pad, all of the inner dimensions of said cage being substantially greater than the corresponding outer dimensions of said ink pad, which is freely and randomly movable therewithin.

8. A stamper as claimed in claim 7 in which the distance between the bottom of said cage and the axis about which said type carrier pivots is less than the distance between said axis and the face of said type, so that when said type carrier is pivoted to bring said type into contact with said pad, said pad is lifted off the bottom of its cage, and when said type carrier is pivoted away from said cage said pad is dropped on the bottom thereof to effect a random displacement thereof.
